Attorney, Agent, or Firm—Townsend F. Beaman

[57] CLAIM

The ornamental design for a rotary joint, substantially as shown and described.

DESCRIPTION

FIG. 1 is a side elevational view of a rotary joint showing our new design, the top, bottom and opposite side being identical to the side shown;

FIG. 2 is a left end elevational view thereof; and

FIG. 3 is a right end elevational view thereof.
